DREDGE-BUCKET PIN.

Application filed November 11, 1920. Serial No. 423,385.

To all whom it may concern:

Be it known that we, JOHN CROUCH, LEWIS D. HOPFIELD, and CHARLES M. ROMANOWITZ, citizens of the United States, residing at Natoma, in the county of Sacramento, State of California, have invented a new and useful Dredge-Bucket Pin, of which the following is a specification in such full and clear terms as will enable those skilled

in the art to construct and use the same.

This invention relates to a dredge bucket pin and its object is to produce a pin which will be easy to take out or put in and which will be a perfectly plain pin loose in its bearings and free to revolve.

It will be understood by those skilled in the art that owing to the size of dredge buckets that the pins are from three to eight inches in diameter and several feet long so that they are very expensive, and owing to the further fact that the dredge buckets are ordinarily made of manganese steel, they are very difficult to machine. Another difficulty is that the freight is very high on machine castings, while with the present invention, the pin is to be placed in position without machining the bucket at all, suitable bushings being used to act as bearings for the pin.

Another object of the invention is to provide means for preventing the end movement of the bucket pin which will enable the bucket to be easily removed from the chain when that is necessary, while at the same time the pin will be securely locked in place and cannot work out of place.

It will of course be understood that with a well fitted bucket lock and pin, there is practically no tendency for the pin to travel endwise when the bucket chain is operating, so that while means must be provided to prevent the pin from working endwise, that such means may be comparatively light.

Other objects of the invention will appear as the description proceeds.

An embodiment of the invention is shown in the accompanying drawings in which the same reference numeral is applied to the same portion throughout, but I am aware that there may be modifications thereof.

Figure 1 is a side elevation of a pair of buckets showing two pins in place and one pin removed.

Fig. 2 is a sectional view along the center line of the pin.

Fig. 3 is a sectional view on the line 3—3 of Fig. 4 of one of the outer bushings.

Fig. 4 is an end view of one of the outer bushings.

The numerals 1 and 2 indicate the two buckets, these buckets have a single lug 3 at one end and two lugs 4 and 5 at their opposite ends. The lugs 4 and 5 are placed apart to embrace the single lugs of the next adjacent bucket of the entire chain. The single lugs are provided with recesses to receive semicircular renewable bushings 6 and 7 and the opening through which the pins 8 pass in the single lug is made so that the pin will fit it loosely.

Lugs 4 and 5 at the opposite end of each bucket are made with openings shaped to receive bushings 9 and 10, these bushings are each provided with flanges 11 and 12, the former flanges extending downwardly from the bushings and being seated in the lugs 4 and 5 to prevent the endwise movement of the bushings when they are in place.

At the outer ends each bushing is provided with a flange 12. This flange projects inwardly and when the bushings are in place in their lugs, prevents the endwise movement of the pin. The holes in the lugs 4 and 5 which receive the bushings 9 and 10 are made large enough so that when the chain is slackened up and two of the buckets pulled toward each other, the pin connecting the two buckets can be removed over the top of the flange 12 on either of the end bushings. When once the pin is removed the buckets separate and the bushings may then be replaced in both the single and the double lugs.

When the bushings have been renewed, the ends of the chain are brought together so that the pin may be driven through the opening in the single lug over the top of the flanges 12 and when seated in place the buckets are allowed to separate by the width of the flanges and the pin is securely held in place. The outer flanges 11 seated

in an opening in the bucket lugs which prevents them from moving lengthwise of the pin.

What we claim is as follows, but various modifications may be made in the construction shown in the drawings and above particularly described form, within the purview of our invention.

A link connector comprising a pin, bushings substantially semi-circular bearing on each end of the pin, flanges on said bushings

to retain the pin in place and to retain them in a link to which they may be applied, and other links bearing on the opposite side of the connecting pin.

In testimony whereof we have hereunto set our hands this 30th day of October, A. D. 1920.

JOHN CROUCH.
LEWIS D. HOPFIELD.
CHARLES M. ROMANOWITZ.
